UNITED STATES PATENT OFFICE.

DESIRÉ V. BOUREAU, OF DETROIT, MICHIGAN.

INTERNAL-COMBUSTION ENGINE.

1,358,513.

Specification of Letters Patent.

Patented Nov. 9, 1920.

Application filed January 26, 1918. Serial No. 213,960.

To all whom it may concern:

Be it known that I, DESIRÉ V. BOUREAU, a citizen of France, who have declared my intention of becoming a citizen of the United States, residing at Detroit, county of Wayne, and State of Michigan, have invented certain new and useful Improvements in Internal-Combustion Engines, of which I declare the following to be a full, clear, and 10 exact description.

This invention relates to improvements in internal combustion engines and more particularly to engines of the two-stroke cycle type.

15 The principal object of my invention is to provide an engine of this type having improved means for scavenging the exhaust gases and subjecting the charge to a preliminary compression.

20 A further object is to provide an improved piston construction of light weight and easily cooled.

A further object of my invention is to provide an engine accomplishing the above 25 objects and in which there is no side thrust on the piston.

A further object of my invention is to provide a very efficient, powerful and quiet engine of the two-stroke cycle type.

30 Further objects, and objects relating to details of construction and economies of manufacture, will definitely appear from the detailed description to follow.

I accomplish the objects of my invention 35 by the devices and means described in the following specification. My invention is clearly defined and pointed out in the appended claims.

40 A structure comprising a preferred embodiment of my invention is illustrated in the accompanying drawing, forming a part of this specification, in which:

Figure I is a view in side elevation of an engine embodying my invention, looking on 45 the valve side of the engine.

Fig. II is an enlarged, vertical, sectional view through the engine, taken on the line II—II of Fig. I, the manifolds and fuel conduits being omitted.

50 Fig. III is an enlarged, fragmentary, sectional view of the piston rod stuffing box, the view corresponding to a part of Fig. II.

Fig. IV is a fragmentary, sectional view taken substantially on the line IV—IV of 55 Fig. II.

Fig. V is a fragmentary, sectional view

taken substantially on the line V—V of Fig. II.

Fig. VI is a fragmentary, detail, sectional view taken substantially on the line VI—VI 60 of Fig. XIII.

Fig. VII is a fragmentary, detail, sectional view taken substantially on the line VII—VII of Fig. II.

Fig. VIII is a transverse, sectional view 65 through the piston.

Fig. IX is an enlarged, detail, sectional view through a part of the piston head corresponding to a part of Fig. II.

Fig. X is a plan view of the cap for closing the recess in the piston head.

Fig. XI is a vertical sectional view through the engine on the line II—II of Fig. I.

Fig. XII is a similar view on the line 75 XII—XII of Fig. I.

Fig. XIII is a similar view on the line XIII—XIII of Fig. I.

Fig. XIV is a similar view on the line XIV—XIV of Fig. I.

Fig. XV is a detail, sectional view on line XV—XV of Fig. I, and

Fig. XVI is a detail, sectional view of the cylinder head showing a modified form of automatic scavenging valve.

In the drawings, similar reference numerals refer to similar parts throughout the several views, and the sectional views are taken looking in the direction of the little arrows at the ends of the section lines.

Considering the numbered parts of the drawing, I have shown an engine comprising a crank case 10 and a cylinder block 11 having a base 12, the crank case 10 and base 12 having coöperating flanges 13 and 14 90 through which the bolts 15 pass to secure the base of the cylinder block to the crank case. In the cylinder block 11 there are formed a plurality of cylinders 16, in this case I have shown four although my invention is not to be restricted to a four-cylinder engine, each cylinder being provided

95 with a skirt 17 extending downwardly into the base 12 of the cylinder block. A liner 18 is inserted in each cylinder 16, said liner having a radially extending flange 19 at its upper end which rests on the upper edge of the cylinder. The liner 18 carries a transversely extending partition 20 dividing the cylindrical liner into an upper and lower 100 part. The cylinder block and crank case

105 may be cast from aluminum and the liners 110

and pistons and other relatively moving parts made of steel and machined and then fitted into the cylinder block. A water jacket 21 is cast integral with the cylinder block and surrounds the cylinders forming the water spaces 22 around the cylinders. Water for cooling may enter the spaces 22 through ports 23.

A plurality of piston-valve chambers 24 10 are cast integral with the cylinder block 11, there being one of these valve chambers for each cylinder and each valve chamber has its axis extending vertically parallel to the axis of the corresponding cylinder. A liner 25 is 15 fitted within each valve chamber 24, each liner having a radially-extending flange 26 at its upper end resting on a corresponding seat, formed at the upper end of the valve chamber, and held in place by the removable 20 cap 27 closing the upper end of the valve chambers.

The valve chambers 24 are all interconnected at their upper ends by the pipes or tubes 28.

25 A cylinder head 29 is removably fastened on the upper end of the cylinder block 11 in any suitable manner, said head having the water spaces 30, communicating with the water spaces 22 of the cylinder block, and 30 the water outlet manifold 31. The head 29 carries at its lower surface the concave surfaces 32 which serve as heads for and close the individual cylinders 16.

The partition 20 in the liner 18 has a central cup 33 having an axial opening therethrough. The vertical wall of this cup is internally threaded at 34 and a flange 35 extends radially inwardly from this vertical wall. An inner cup 36 seats in the axial 40 opening of the cup 33 having an outwardly extending flange which seats on the flange 35 and having an axial opening therethrough. A ring of soft bearing metal 38 rests in cup 36 and a ring of hard metal 39 45 seats on said ring, being retained in place by the retaining cup 41 which rests on another soft metal ring 40 disposed on top of the ring 39. The cup 41 has an axial opening 42 therethrough in line with the opening 37 in the cup 36 and an externally threaded part 43 screwing into the internally threaded part of the cup 33. The cup 41 has on its lower edge a beveled flange 44 which engages a similar flange on the cup 36 to make a 50 tight seat.

55 A cross-head 45, which is cylindrical in cross-section, works in the lower part of the cylinder below the partition 20 and the piston rod 47 is integral with the cross head 60 and extends upward and axially therefrom through the openings 37 and 42 in the stuffing box and through the bearing rings 38, 39 and 40 into the cylinder 16. The upper end 48 of the piston rod 47 is tapered 65 and seats in a corresponding tapered seat in

the hub 50 of the piston which works in the cylinder 16. The piston is of skeleton formation so as to reduce its weight and facilitate cooling and comprises an outer cylindrical wall 49 connected with and supported 70 from the hub 50 by means of a plurality of radiating fins or walls 51. These walls 51 and the hub 50 are cut away at the top to form a chamber 52 which accommodates the nut 53 threaded on the upper end of the piston rod 47 to retain the hub 50 of the piston thereon. The head 54 of the piston is concave and has an axial opening therein closed by a cap 55, externally threaded at 57, and screwed into the opening, said cap having a 80 beveled flange 58 engaging a corresponding seat in the head 54. This arrangement permits the cool air drawn into the lower part of the cylinder below the piston to circulate freely in contact with the inner surface of 85 the piston head and wall so as to greatly facilitate the cooling of the piston. A plurality of sockets 59 are formed in cap 55 into which the teeth of a suitable tool may be introduced in removing the cap. 90

A concave recess 60 is formed in the lower part of cross-head 45 and the upper end of connecting rod 62 is pivotally mounted on the pin 61 carried by the cross-head. The lower end of the connecting rod 62 is connected with the arm 63 of the crank shaft 64 which is suitably journaled in the crank case. A gear 65 is mounted on the crank shaft, at one end of the case, and meshes with a suitably journaled idle gear 66, which 100 meshes with a gear 67 mounted on the counter crank shaft 68 which is also suitably journaled in the base of the cylinder block. The lower end of connecting rod 70 is connected to arm 69 of the counter crank shaft 105 68. The upper end of the connecting rod is pivotally connected to a pin 71 carried at the lower end of piston valve 72.

The exhaust port 73 is provided in the side wall of the cylinder 16, about midway 110 between the upper end of the cylinder and the partition 20. A port 74 is formed in the outer side wall of each valve chamber 24 and each of these ports is in communication with one of the branches of an intake manifold 76 which connects with a carburetor 77. A second port 75 is also provided, in the side wall of each valve chamber 24, communicating with the open air through an air intake manifold, (not shown), in which a 115 suitable control valve may be mounted to control the intake of air for scavenging and cooling the piston. A transverse port 78 is provided in the piston valve in such a position that it may align with either port 74 or 120 75 depending upon the position of the piston valve. A port 79 connects the valve chamber 24 with cylinder 17 below the partition 20 and a similar port 80 connects the valve chamber with cylinder 16 above the 130

partition 20, the ports 79 and 80 being in line with ports 74 and 75, respectively.

A port 81 is formed in the side wall of the valve chamber 24 near the upper end thereof and a coöperating port 83 connects the valve chamber 24 and cylinder 16, port 83 being so located that it is only uncovered by the piston during the lower half of the piston stroke. An inclined port 82 is formed in the piston valve which port, at certain positions of the valve, connects the ports 81 and 83. A relief port 84 extends transversely of the piston valve 72, above the port 82, being so disposed that, when the piston uncovers port 83 on the power stroke, the port 84 is in line with the port 83 and with a recess 85 formed in the outer side wall of the valve chamber. A port 86 extends through the side wall of cylinder 17, just below the partition 20, and this port is connected with the port 81 feeding one of the other cylinders by means of a pipe or conduit 91. These pipes connecting the ports 86 and the ports 81 are so arranged that each cylinder feeds compressed gas to the cylinder which fires next in order after it. In the drawings, the crank shaft is such that the cylinders fire in the order A, B, D, C, and cylinder A feeds B, B feeds D, D feeds C, and C feeds A. If the firing order is different the arrangement of the pipes 91 will, of course, be different but, in any event, each cylinder feeds to the one next to fire.

Passages 92 are cored in the cylinder block each of which communicates at its lower end with a port 93 opening into one of the cylinders 16 just above the partition 20. Passages 94 are formed in the cylinder head which connect with the upper ends of passages 92 in the cylinder block. Each of these passages 94 opens into a transversely extending cylindrical passage 95 in the cylinder head, there being one of these passages extending above each of the cylinders. Each passage 95 has an enlarged portion or chamber 96 in which is seated a cylindrical slide valve 97 having a skirt 98 extending from the forward end thereof and having a beveled edge seated on a corresponding seat at the end of chamber 96. Each skirt has a plurality of ports 100 therethrough and there is a groove 101 in the side wall of chamber 96 connected by port 90 with the engine cylinder. A compression spring 102 is seated behind the valve 97 and held in place by cap 103 closing the end of chamber 96 and having a vent 104 therethrough. A suitable spark plug, (not shown), is provided for the combustion chamber of each cylinder.

A wide groove 105 is cut in the side of piston valve 72, and an oil port 106 extends through the side of the valve chamber 24 at such a point that it communicates with groove 105 at all points of the piston valve

stroke. The oil ports 107 are connected with the branches 106 of an oil manifold connected with a pressure lubricating system.

In Fig. XVI, I have shown a modified form of automatic scavenging valve in which the head 29 has passages 110 connecting with the passages 92 in the cylinder block. A chamber 111 is formed over each cylinder and each of the passages 110 connects with one of the chambers 111, said chambers being connected with the respective cylinders by ports 112. A supporting member 113 is provided in each cylinder 111 and the valve stem 114 of the valve 115, normally closing port 112, is slidably mounted in said member 113. A spring 116 is compressed between member 113 and washer 117 carried by the upper end of the valve stem. Chamber 111 is closed by the removable cap 118.

From the description of the parts given above, the operation of this engine should be very readily understood. This engine is of the two-stroke cycle type in which an explosion occurs at each complete stroke of the piston. Furthermore the charge ignited is given a preliminary compression before passing into the combustion chamber where it receives a final compression before explosion takes place. I have also provided means for scavenging the combustion chamber very effectively and for cooling the piston by directing cool air in contact with the walls thereof.

In Figs. XI, XII, XIII and XIV, I have shown the engine in four different positions of the crank shaft, ninety degrees apart. In Fig. XI the explosion has just occurred and the piston is starting on its down stroke. Air, which has previously been drawn into the cylinder below the piston is compressed between the piston and the partition 20 on the down stroke. The piston valve 72 moves down with the piston and brings port 78 in line with ports 74 and 79 so that a fresh charge is sucked into cylinder 17 in which the cross head 45 is descending. During the entire down stroke of the piston gas is drawn into the pre-compression chamber in the cylinder 17 between partition 20 and cross head 45. At the end of the down stroke of the piston the piston valve 72 is moving up and port 78 is just moving out of line with ports 74 and 79. As the piston moves up on its return stroke, the gas drawn into the pre-compression chamber is compressed by the upwardly moving cross head 45 to give a preliminary compression to the gas. The pre-compression chamber of each cylinder is connected to the combustion chamber of the cylinder next to fire by a pipe 91 through the ports 81 and 83 and the inclined port 82 of the piston valve 72. As the piston starts on its up stroke, the piston valve is moving up and, at the instant that the upwardly

moving piston closes, the exhaust port 73, the piston valve has moved so that port 82 is in line with ports 81 and 83 and a charge of gas, which has been compressed in the 5 precompression chamber of the cylinder about to fire, rushes in, through these ports 81, 82 and 83, to the combustion chamber and is given a further compression by the piston as it moves upwardly to top dead center at or near which the explosion occurs.

As the piston moves up on its up stroke, air is drawn in, through ports 75, 78 and 80, to the pump chamber formed in the lower part of the cylinder 16 between the piston 15 and the partition 20. When the piston starts on its down stroke, the piston valve has moved down so that port 78 and ports 75 and 80 are out of line and consequently the air compressed in the pump chamber by the 20 descending piston is forced through port 93 and passages 92 and 94 against the end of the valve 97. The pressure of spring 102 is regulated so that the air pressure does not counteract the pressure of the spring until 25 the beginning of the last half of the down-stroke of the piston and then the air pressure forces the valve 97 back and the compressed air enters the combustion chamber through passage 95, ports 100, groove 101 30 and passage 90. This cool air rushing down into the combustion chamber assists in driving the burned gases out through the exhaust port which is uncovered by the piston about this time and thus insures a thorough scavenging of the combustion chamber. Furthermore the cool air rushing in assists materially in cooling the cylinder and piston walls thus eliminating all danger of pre-ignition. The gas left in the combustion chamber 40 which mingles with the fresh charge is fresh air admitted under pressure instead of burnt gases as in other types of two-cycle engines and hence a more efficient operation is secured.

45 When the piston starts up on its up-stroke the air pressure drops and the spring 102 returns the valve 97 so that it closes the port 90 which leads into the combustion chamber. A relief port 84 is provided in the piston valve 72 which port is in line with port 83 and recess 85 when port 83 is uncovered by the piston on the down-stroke and consequently the side thrust or pressure due to the expanding gases is transmitted to the 50 wall of the valve chamber and does not act on the piston valve.

The piston is of skeleton formation and is consequently very light. Furthermore the air drawn into the pump chamber passes 60 freely around the hub 50 of the piston in contact with the inside of the piston wall and head and hence the piston can be very readily kept cool, the heat generated by the explosion being to a certain extent transmitted to the air which is in the pump

chamber and in contact with the inner piston walls. Furthermore the mass of metal in the piston is not great and the retention of heat in the piston is consequently small. The cross head 45 really serves as a supplemental piston and the piston rod 47 is an integral part of the cross head. The piston is compelled to move in straight rectilinear lines and all side thrust is taken up by the cross head 45 and the piston rod 47 which reciprocates in the stuffing box formed in the partition 20. Consequently there is no side slap of the piston. The cross head not only serves to take up the side thrust from the crank shaft but also acts as the piston 70 working in the precompression chamber to give a preliminary compression to the charge. The combustion and pump chambers are surrounded by a water jacket 21 so that they may be efficiently cooled and 75 the cooling water enters the jacket from water manifolds, (not shown), above and below the exhaust port 73, so that the coolest water in the system comes in contact with the parts where the heat is likely to 80 be greatest.

The cross heads 45 are connected to the throws 63 of crank shaft 64 by connecting rods 62 and the force of the explosion is transmitted from the piston through piston 95 rod 47 to cross head 45 and from the latter through connecting rod 62 to the crank shaft 64 to drive the latter. The crank shaft 64 drives the counter-crankshaft 68 through the meshing gears 65, 66 and 67. 100 The counter-crankshaft turns in the same direction and at the same speed as the crankshaft. The piston valves are driven from the counter-crankshaft through connecting rods 70 and the throws of the counter-crankshaft are so arranged that the top dead center of the piston valve stroke occurs a little less than a quarter of a revolution earlier than the top dead center of 105 the piston stroke. The piston valves 72 each work in a cylindrical valve chamber 24 opening at its lower end into the crank case and closed at its upper end by cap 27. The upper ends of the valve chambers are connected by pipes 28 so that the air pressure 110 in the upper ends of the valve chambers will equalize through these pipes. A groove 105 is cut in the side of the piston valve 72 and oil is admitted through pipe 107 and port 106 so as to lubricate the piston valve. 115

In Fig. XVI, I have shown a modified automatic valve which may be used in place of the valve 97 shown in the other views.

When the pressure in the pump chamber exceeds the pressure of spring 116, valve 115 will open and a jet of scavenging air will enter the cylinder from passages 92, 110 and through port 112. The valve closes automatically when the pressure drops.

In the description above, I have referred 130

to the combustion chamber, the pump chamber and the precompression chamber. By the combustion chamber, I mean that part of each cylinder limited above by the cylinder head and below by the piston head. By the pump chamber, I refer to that part of each cylinder between the piston and the partition 20 and, by the precompression chamber, I mean that part of each cylinder 5 below the partition 20 and above the cross head 45.

In the form of my engine herein illustrated, the pump chamber is used to compress air for scavenging the combustion chamber and the charge is preliminarily compressed in the precompression chamber. This is the preferred form of my engine but, if desired, the port 75 might be connected with intake manifold 76 and both pump chamber and 10 precompression chamber used to compress the charge which is fed to the combustion chamber. The connections might also be so arranged that the air for scavenging is compressed in the precompression chamber 15 and the fresh charge compressed in the pump chamber. I contemplate both of these arrangements, as well as numerous others, which will occur to those skilled in the art, as within the spirit of my invention. 20 30 I have illustrated a four cylinder engine but my invention is not limited to this as the principles here disclosed are not dependent on the number of cylinders in the engine.

35 I am aware that the particular embodiment of my invention, here shown and described, is susceptible of considerable variation without departing from the spirit thereof and, therefore, I desire to claim my 40 invention broadly, as well as specifically, as indicated by the appended claims.

Having thus described my invention, what I claim as new and desire to secure by Letters Patent, is:

45 1. In an engine of the class described, the combination of a plurality of cylinders, each provided with an exhaust port uncovered by the piston toward the end of the power stroke, and an intake port disposed 50 in a plane just above the exhaust port; a piston working in each cylinder; a crank-shaft driven by said pistons; means for preliminarily compressing a charge of gas; means for injecting a scavenging jet of air 55 through the upper end of each cylinder toward the end of the power stroke; means for injecting a compressed charge through said intake port toward the beginning of the compression stroke; a piston valve driven by 60 the crankshaft for controlling said intake port; and a pressure-operated valve for controlling the scavenging jet.

65 2. In an engine of the class described, the combination of a plurality of cylinders closed at both ends; a piston working in

each cylinder and dividing it into upper and lower chambers; a crank shaft driven by said pistons; an air intake port opening into said lower chamber; a gas intake port opening into said upper chamber; a single valve 70 controlling said air and gas intake ports; a passage connecting said upper and lower chambers; and a pressure operated valve in said passage.

3. In an engine of the class described, the combination of a plurality of cylinders closed at both ends; a piston working in each cylinder and dividing it into upper and lower chambers; a crank shaft driven by said pistons; an air intake port opening 80 into said lower chamber; a gas intake port opening into said upper chamber; a single slide valve driven from said crank shaft and controlling both said ports; a passage connecting said upper and lower chambers; 85 and a pressure-operated valve in said passage.

4. In an engine of the class described, the combination of a plurality of cylinders closed at both ends; a piston working in 90 each cylinder and dividing it into upper and lower chambers; a crank shaft driven by said pistons; an air intake port opening into said lower chamber; a gas intake port opening into said upper chamber; a piston 95 valve reciprocable in a path parallel to the piston and driven by said crank shaft, said piston valve controlling both said ports; a passage connecting said upper and lower chambers; and a pressure operated valve 100 in said passage.

5. In an engine of the class described, the combination of a plurality of cylinders, each cylinder including a combustion chamber, a pump chamber and a precompression 105 chamber all in axial alinement; a piston for each cylinder having an upper head working in the combustion and pump chambers and a lower head working in the precompression chamber; a crank shaft driven by said pistons; an intake port for each of said pump chambers; an intake port for each of said combustion chambers; a passage connecting the pump chamber and the combustion chamber; a pressure operated valve in said 110 passage; valves controlling said intake ports; and passages connecting each precompression chamber with the intake port of the combustion chamber of the cylinder firing next succeeding.

6. In an engine of the class described, the combination of a plurality of cylinders, each cylinder including axially alined combustion, pump and precompression chambers; a piston for each cylinder having an upper head working in two of said chambers and a lower head working in the third chamber; a crank shaft driven by said pistons; intake ports for each of said chambers; passages connecting the pump and 125 130

3
combustion chambers of each cylinder; pressure-operated valves in said passages; valves controlling said intake ports; and passages connecting the precompression chambers 5 with the combustion chambers of the cylinders firing next succeeding.

7. In an engine of the class described, the combination of a plurality of cylinders, each cylinder including axially alined combustion, pump and precompression chambers; a piston for each cylinder having an upper head working in two of said chambers and a lower head working in the third chamber; a crankshaft driven by said pistons; intake 10 ports for each of said chambers; passages connecting the pump and combustion chambers of each cylinder; pressure-operated valves in said passages; a single slide-valve controlling at least two of the intake ports 15 for each cylinder; and passages connecting each precompression chamber with the intake port of the combustion chamber of the cylinder firing next succeeding.

8. In an engine of the class described, the combination of a plurality of cylinders, each cylinder including axially alined combustion, pump and precompression chambers; a piston for each cylinder having an upper head working in two of said chambers and a lower head working in the third chamber; a crankshaft driven by said pistons; intake 20 ports for each of said chambers; passages connecting the pump and combustion chambers of each cylinder; pressure-operated valves in said passages; piston valves driven by the crankshaft and reciprocable in paths 25 parallel to the pistons, each piston valve controlling at least two of the intake ports of the corresponding cylinder; and passages connecting each precompression chamber 30 with the intake port of the combustion chamber of the cylinder firing next succeeding.

9. In an internal combustion engine of the class described, the combination of a cylinder block having plurality of cylinders, each cylinder including axially alined combustion, pump and precompression chambers; a piston for each cylinder having an 45 upper head working in two of said chambers and a lower head working in the third chamber; a crankshaft driven by said pistons; intake ports for each of said chambers; 50 passages cored in said cylinder block and connecting the pump and combustion chambers of each cylinder; pressure-operated valves in said passages; piston valves driven by said crankshaft and reciprocable in paths parallel to the pistons, each piston-valve controlling at least two of the intake ports of the corresponding cylinder; and passages connecting each precompression chamber with the intake port of the combustion chamber of the cylinder firing next succeeding.

bers; passages cored in said cylinder block and connecting the pump and combustion 55 chambers of each cylinder; pressure-operated valves in said passages; piston valves driven by said crankshaft and reciprocable in paths parallel to the pistons, each piston-valve controlling at least two of the intake 60 ports of the corresponding cylinder; and passages connecting each precompression chamber with the intake port of the combustion chamber of the cylinder firing next succeeding.

10. In an internal combustion engine, the combination of a plurality of cylinders; a partition wall dividing each cylinder into an upper and a lower portion; pistons each having a head working in the upper portion of the cylinder and a head working in the lower portion thereof; a crank shaft driven by said pistons; an intake port for the lower portion of each cylinder; a pair of intake 70 ports for the upper portion of each cylinder; a single slide valve for each cylinder controlling said intake ports; passages connecting the top and bottom of the upper portion of each cylinder; pressure-operated valves in said passages; and passages connecting the lower portion of each cylinder 75 with the upper intake port of the cylinder firing next succeeding.

11. In an internal combustion engine, the combination of a plurality of cylinders; a partition wall dividing each cylinder into an upper and a lower portion; a piston working in each of said lower portions; connecting rods slidably mounted in said partition walls and carried by said pistons; upper 80 pistons secured to the upper ends of said connecting rods and working in the upper portions of said cylinders; a crankshaft driven by said pistons; an intake port for the lower portion of each cylinder; a pair of intake 85 ports for the upper portion of each cylinder; a single slide valve for each cylinder controlling said intake ports; passages connecting the top and bottom of the upper portion of each cylinder; pressure-operated valves in said passages; and passages connecting the lower portion of each cylinder 90 with the upper intake port of the cylinder firing next succeeding.

In testimony whereof I affix my signature. 105
DESIRÉ V. BOURREAU.
